his ATTORNEY

UNITED STATES PATENT OFFICE.

AUGUST AHLBRECHT, OF PITTSBURGH, PENNSYLVANIA.

AEROPLANE.

1,201,911.

Specification of Letters Patent. Patented Oct. 17, 1916.

Application filed May 1, 1915. Serial No. 25,156.

To all whom it may concern:

Be it known that I, AUGUST AHLBRECHT, a citizen of the United States, residing at Pittsburgh, in the county of Allegheny and 5 State of Pennsylvania, have invented a new and useful Improvement in Aeroplanes, of which improvement the following is a specification.

My invention relates to improvements in 10 aeroplanes, particularly to the construction of bi-planes, and has for its object to provide simple and effective means to prevent dangerous tipping or overturning of the bi-plane and to reestablish its balance when disturbed by cross currents or pockets in the air. I accomplish this object by means of the 15 novel construction and arrangement of parts hereinafter more specifically described, reference being had to the accompanying drawings, forming part hereof, in which—

Figure 1 is a perspective view of a bi-plane showing my improvement applied. Fig. 2 is a diagram illustrating the general arrangement of the various planes.

25 Referring to said drawings, 1, indicates an aeroplane frame, which may be of any suitable form or construction, 2, is the lower sustaining plane or aerofoil secured to said frame, at each side of which are rigidly secured the outwardly and upwardly inclined balancing planes, 3, which are preferably disposed at an angle of approximately thirty degrees, said planes forming practically a continuation of the lower sustaining plane, 30 2. Immediately above the balancing planes, 3, are arranged the balancing planes, 4, which are likewise secured to the framework some distance above the balancing planes 3, and are outwardly and upwardly 35 inclined at approximately the same angle of thirty degrees to a height somewhat above the upper sustaining aerofoils, and each terminating at its upper edge in an outwardly extended deflector, 5, the surface of these 40 planes being preferably of larger area than the lower balancing planes.

Centrally and oppositely inclined balancing planes, 6, are suitably secured to the frame supports, separated at their lower 45 edges to provide an open space therebetween for the passage of air and the planes of each of which extend upwardly and outwardly at an angle of approximately thirty degrees to a greater height above the upper sustaining planes than the balancing planes,

4, and being each flanged outwardly at their upper edges to form the deflectors 7.

8, 9, and 10, indicate sections of the upper sustaining planes or aerofoils, the aerofoil section 8 being located between the upper 60 balancing plane 4 and the central balancing plane 6 and so disposed that there is a space for the passage of air at the sides adjacent said balancing planes. The central aerofoil section, 9, is located between the central balancing planes and is also separated therefrom by an open air space at each side thereof adjacent said central balancing planes. Aerofoil section 10 is located between the balancing planes 4 and 6 at the 65 right hand side as indicated in the diagram Fig. 2, being also separated from each of said balancing planes by an opening or air space at each side thereof.

70 It will be seen that an aeroplane provided with my improved construction, when encountered by a cross current flowing toward one side thereof, as, for instance, at the left side, then said current acts upon the underside of the balancing planes thereat, 75 raising the left side of the aeroplane and causing same to dip and tend to descend to the right. At the same time, the pressure of the sustaining air layer on the right side acts on the underside of the right hand balancing planes and on the upper sides of the left hand balancing planes after having passed between the lower and upper aerofoils there-to, causes the aeroplane to slide or skid upon the air layer to the right, until it again becomes righted to its normal position.

75 During the above described action of a current of air acting on the left of the aeroplane, the deflector 5 on the balancing plane 4, at the right side, and the deflector 7, at the right of the central balancing plane 6 tends to deflect or guide the air to the underside of the balancing plane of which it forms a part. Furthermore, the balancing planes 4 and 6 being extended above the sustaining planes or aerofoil sections 8, 9 and 10, the flow of air over the upper portion of the deflectors 5 and 7 is prevented from coming into immediate or direct contact with the upper side of the sustaining aerofoil sections thereat, during dipping, causing the air from the right to act upon the upper surface portion of said sustaining plane at the left or elevated side, thereby assisting in establishing the balance. 100 105 110

By providing an aeroplane with balancing planes such as described, it will be readily apparent that the same will be automatically righted to its normal horizontal position, no matter as to which side the current of air may flow or tend to disturb its balance.

I claim as my invention and desire to secure by Letters Patent:

10. 1. In an aeroplane, the combination of a lower sustaining plane having an inclined balancing plane positioned rigidly at each side thereof and constituting a continuation thereof, said balancing planes being oppositely inclined and having their outer edges uppermost, rigidly fixed balancing planes above the aforesaid balancing planes and at a like inclination thereto, centrally disposed rigidly fixed and oppositely inclined balancing planes located above the lower sustaining plane, and upper sustaining planes or aerofoils formed of sections, one of said sections being disposed between the central balancing planes, leaving an air space therebetween, and the other sections between the said central and the upper side balancing planes, having air spaces therebetween.

25. 2. In an aeroplane, the combination of a lower sustaining plane having an inclined balancing plane positioned rigidly at each side thereof and constituting a continuation thereof, said balancing planes being oppositely inclined and having their outer edges uppermost, rigidly fixed balancing planes above the aforesaid balancing planes and at a like inclination thereto, centrally disposed rigidly fixed and oppositely inclined balancing planes located above the lower sustaining plane, the upper ends thereof extending

above the upper edges of the upper balancing planes, and an upper sustaining plane formed of sections, one of said sections being disposed between the central balancing planes, having an air space therebetween, and the other sections between said central and upper side balancing planes having air spaces therebetween. 45

3. In an aeroplane, the combination of a lower sustaining plane having an inclined balancing plane positioned rigidly at each side thereof and constituting a continuation thereof, said balancing planes being oppositely inclined and having their outer edges uppermost, rigidly fixed balancing planes above the aforesaid balancing planes and at a like inclination thereto, centrally disposed rigidly fixed and oppositely inclined balancing planes located above the lower sustaining plane, the upper ends thereof extending above the upper edges of the upper balancing planes, and an upper sustaining plane formed of sections, one of said sections being disposed between the central balancing planes, having air spaces therebetween, and the other sections between said central and upper balancing planes having air spaces therebetween, said upper side balancing planes and said central balancing planes being each provided with a turn-over deflector portion at the upper edges thereof.

In testimony whereof, I have hereunto signed my name in the presence of two subscribing witnesses.

AUGUST AHLBRECHT.
